VENEER FASTENING MEANS

Filed Jan. 16, 1935

UNITED STATES PATENT OFFICE

2,005,030

VENEER FASTENING MEANS

Nelson O. Geisinger, Dover, Ohio

Application January 16, 1935, Serial No. 2,080

9 Claims. (Cl. 72—19)

My invention relates generally to the application of veneer to walls, said veneer being composed of relatively thin blocks, tiles or bricks and the like, and more particularly to fastening means for maintaining veneering units in position on a wall before the mortar is applied to the joints of the units.

Certain prior veneer wall constructions have provided means for holding the veneering units on the wall before the mortar is applied, but the members which engage the units are easily bent or displaced so as to throw the units out of alignment, with the result that the veneer presents an unsightly appearance after the mortar is applied.

It is therefore an object of the present invention to provide improved veneer fastening means which will positively maintain veneering units in proper position and alignment on a wall.

Another object is to provide improved veneer fastening means which is easily applied to a wall, and which can be applied to a whole section of the wall before the veneering units are applied.

A further object is to provide improved veneer fastening means which requires a minimum of time and material, and in which the veneering units are easily and quickly secured on the wall.

Another object is to provide improved veneer fastening strips adapted for permitting expansion and contraction thereof without disturbing the means attaching the strips to the wall.

A further object is to provide improved veneer fastening means to which each veneering unit is easily applied and then individually clamped and interlocked without danger of chipping or breaking the edges of the units.

A still further object is to embody all of these features in a simple and inexpensive construction which provides for great flexibility in the application of the veneer covering.

These and other objects are attained by the improvements comprising the present invention which may be stated in general terms as including fastening strips adapted to be attached to a wall at intervals, each strip being U-shaped in cross section and having a series of projections thereon for securing a plurality of veneering units in spaced relation, the units having grooved opposite surfaces for receiving the projections, the projections at one side of each unit being pre-formed to fit in the adjacent groove in the unit when the unit is applied, the projections at the opposite side of each unit being adapted to be bent into interlocking engagement with the adjacent groove of said unit after said unit is applied, and there being slots in the sides of the

fastening strips for receiving and supporting the veneering units in proper alignment.

Referring to the drawing forming part hereof, Figure 1 is a fragmentary elevation of a wall having a veneer secured thereto by the improved fastening means;

Fig. 2 is a sectional view thereof, as on line 2—2, Fig. 1;

Fig. 3 is a detached fragmentary perspective view of one of the improved fastening strips;

Fig. 4 is a fragmentary sectional view similar to Fig. 2, showing the strip in elevation, and the method of bending alternate projections into interlocking engagement with adjacent grooved surfaces of the veneering units;

Fig. 5 is a plan view thereof;

Fig. 6 is a fragmentary perspective view of the bending tool; and

Fig. 7 is a detached perspective view of one of the veneering units.

Similar numerals refer to similar parts throughout the several views of the drawing.

In Figs. 1 and 2 is shown a portion of a building wall indicated generally at 10 and constructed of siding, which may be tongue and groove siding 11 secured to studding in the usual manner. Preferably, the outer surface of the siding 11 is first covered with some form of insulating material shown at 12 before applying the improved veneer fastening means.

The veneer wall shown in the drawing and described herein is formed of veneer bricks 13, but other veneering units can be substituted therefor without departing from the scope of the invention as defined in the appended claims.

The improved veneer fastening means preferably includes the U-shaped or channel-shaped strips 14 having the web 15 and side flanges 16. These strips are preferably formed from sheet metal and may be galvanized or otherwise rust proofed.

The strips 14 are applied to the wall preferably in vertically extending rows, as shown in Fig. 1, the rows being preferably horizontally spaced apart a distance less than the length of one of the veneer bricks 13 to be fastened thereby, so that each brick will be fastened by two strips as shown in Fig. 1.

Each strip 14 is provided with longitudinally spaced projections punched out of the web 15 and preferably extending from the web in the same direction as the side flanges 16. The projections are spaced longitudinally of the strip in such manner that a veneer brick 13 will fit between each pair of projections, and so that the

bricks after being fitted in the projections will be spaced vertically so as to allow for horizontal mortar joints, as indicated at 17.

Each brick or veneering unit 13 is provided with 5 grooved opposite surfaces, that is, the upper and lower surfaces of the brick are provided with longitudinal grooves indicated at 18. The lower projection 19 of each pair between which a brick 13 fits is preformed to fit or interlock in the lower 10 groove 18 of the brick. In other words, the lower projection 19 of each pair has its outer end 20 bent upwardly before the bricks are applied, so that when the bricks are applied one between each pair of projections the outer end 20 of each 15 projection 19 will enter into and interlock with the lower groove 18 of a brick 13.

The alternate projections 21, that is, the projections which engage the upper surface of the bricks, are formed substantially at right angles 20 to the web 15 of the strip. Preferably the projections 21 are slightly curved laterally of the strip for a purpose to be hereinafter described.

Substantially midway between each pair of projections 20 and 21, the web 15 of each strip is formed or curved outwardly in a substantially spherical portion, as shown at 23 in Figs. 2 and 3, and a hole 24 is provided in the curved portion 23 through which the nails 25 or other means pass for attaching the strips to the wall. Preferably the holes 24 are somewhat elongated longitudinally of the strip for a purpose to be hereinafter described.

Preferably each side flange 16 of the strips is provided with slots indicated at 26 laterally adjacent to each pair of projections 19 and 21 for receiving the veneer brick 13 which is fastened by that pair of projections, and for supporting that brick in alignment with other bricks on the wall. The slots 26 form lugs 28, the upper surfaces 29 of which are preferably at right angles to the web 15, and substantially in the same plane as and laterally adjacent to the projections 19, so that they act to support a veneer brick 13 in horizontal position. By applying all 40 of the strips 14 to the wall 10 in such manner that the surfaces 29 of the lugs are in horizontal alignment, the horizontal alignment of all of the bricks in each course is positively maintained.

In applying the improved veneer wall construction, the improved fastening strips 14 are first attached to the wall in vertical rows by means of nails 25 and the like passing through holes 24 into the siding 11, and the upper surfaces 29 of the brick supporting lugs 28 are located in horizontal alignment. The elongated holes 24 provide for slight longitudinal adjustment of the strips as they are being fastened, so as to facilitate alignment of the lugs 28. The curved or spherical portions 23 of the strips provide for 55 maintaining a positive clinching action between the nail heads and the strips to hold the strips tightly against the wall regardless of expansion and contraction of the strips after they are in place.

60 After a relatively large section of the wall surface has had the securing strips attached thereto in this manner, the veneer bricks 13 are applied. These bricks are adapted to be inserted one between each pair of projections 19 and 21 as best shown in Fig. 2, and each brick 13 is preferably tilted slightly as it is inserted between the projections so that its lower groove 18 receives the end 20 of the preformed projection 19.

65 After the bricks 13 have been inserted in this manner they may be slid horizontally in the strips

in order to space them horizontally sufficiently to provide for the vertical mortar joints indicated at 30, and in this manner the vertical mortar joints may be slightly varied to accommodate the bricks to irregularities in the wall.

After the bricks have been thus inserted between the pairs of projections, the upper projection 21 of each pair may be bent downwardly at its outer end into interlocking engagement with the upper groove 18 of the brick. A special tool 10 may be provided for this purpose such as is shown at 32 in Fig. 5, and has a protuberance 33 on its underside for engaging the projection 21, and lateral ears 34 for bearing upwardly upon the lower surfaces 35 of the lugs 28. Preferably, the lower 15 surfaces 35 of lugs 28 are slightly undercut as shown to aid in preventing accidental withdrawal of the tool during the bending operation.

The tool 32 is inserted in a position such as shown in dot-dash lines in Fig. 4, with the protuberance 33 bearing on top of a projection 21 to be bent and the ears 34 extending under the lower surfaces 35 of laterally opposite lugs 28. By forcing the tool downward to the full line position, the protuberance 33 bends the projection 25 21 into interlocking engagement with the upper groove 18 of a veneer brick, as shown.

Since the projections 21 are slightly curved laterally, the projection grips or clinches the brick at both sides of the projection instead of at 30 one point only, as might be the case if the projection were flat. Also the laterally curved shape of the projection 21 strengthens the same so as to prevent springing back thereof after the bending tool is withdrawn.

35 The supporting lugs 28 provide for positively maintaining the veneering units of each course in proper alignment on the wall because the bricks are supported on the upper surfaces of the lugs instead of on the easily bent projections on the 40 web. Moreover, when the upper projection 21 of each pair is bent into interlocking engagement with the upper grooved surface of each brick, the action of the clamping tool 32 is to force the brick downwardly against the solid supporting 45 lugs 28, so that the alignment of the bricks is not affected.

Due to the fact that the horizontal spacing of the strips may be varied slightly to fit irregularities in the wall, and that the bricks may be moved 50 horizontally after being inserted between the pairs of projections, the present improved veneer construction provides the same flexibility during construction as is present in the laying up of an ordinary brick wall by a mason.

55 The veneering bricks or units are easily applied and interlocked in the improved fastening means without danger of chipping or breaking the edges of the bricks, and the improved fastening means 60 are simple and inexpensive to manufacture and to install.

Obviously, the improved fastening strips may be arranged on the wall in inverted position, or in horizontal rows instead of vertical rows without 65 departing from the scope of the invention as defined in the appended claims.

I claim:—

1. In veneer wall construction, a wall, spaced strips on the wall, means attaching the strips to 70 the wall, each strip being U-shaped in cross section and having longitudinally spaced projections, a plurality of veneering units each fitting between a pair of said projections, and there being slots in the sides of each strip in which said ve- 75

- neering units are received and supported in alignment with other units on the wall.
2. In veneer wall construction, a wall, spaced strips on the wall, means attaching the strips to the wall, each strip being U-shaped in cross section and having longitudinally spaced projections, a plurality of veneering units each having grooved opposite surfaces and fitting between a pair of said projections, one projection of each pair being preformed to fit in the adjacent groove of a unit when the unit is applied and the other projection of said pair being adapted to be bent into interlocking engagement with the opposite groove of said unit after the same is applied, and there being slots in the sides of each strip in which said veneering units are received and supported in alignment with other units on the wall.
3. In veneer wall construction, a wall, spaced strips on the wall, means attaching the strips to the wall, each strip having longitudinally spaced projections intermediate its sides, a plurality of veneering units each fitting between a pair of said projections, and means at the sides of each strip for supporting said veneering units therein in alignment with other units on the wall.
4. In veneer wall construction, a wall, spaced strips on the wall, means attaching the strips to the wall, each strip having longitudinally spaced projections intermediate its sides, a plurality of veneering units each having grooved opposite surfaces and fitting between a pair of said projections, one projection of each pair being preformed to fit in the adjacent groove of a unit when the unit is applied and the other projection of each pair being adapted to be bent into interlocking engagement with the opposite groove of said unit after the same is applied, and means at the sides of each strip for supporting said veneering units therein in alignment with other units on the wall.
5. In veneer wall construction, a wall, spaced strips on the wall, means attaching the strips to the wall, each strip having longitudinally spaced projections intermediate its sides, a plurality of veneering units each having grooved opposite surfaces and fitting between a pair of said projections, one projection of each pair being preformed to fit in the adjacent groove of a unit when the unit is applied and the other projection of each pair being adapted to be bent into interlocking engagement with the opposite groove of said unit

after the same is applied, and veneering unit supporting lugs at the sides of each strip, the upper surface of each supporting lug being laterally adjacent to a preformed projection for supporting a unit in alignment with other units on the wall, and the lower surface of each supporting lug being adapted to bear against a tool during the bending of another projection into interlocking engagement with the groove in another veneering unit.

6. In veneer wall construction, a wall, spaced strips on the wall each having longitudinally spaced projections, a plurality of veneering units each fitting between a pair of said projections, and means extending through the strips between the projections for attaching the strips to the wall, there being curved portions formed in the strips adjacent the attaching means for permitting expansion and contraction of the strips without disturbing the attaching means.

7. In veneer wall construction, a wall, spaced strips on the wall, means attaching the strips to the wall, each strip having longitudinally spaced projections intermediate its sides, a plurality of veneering units each having grooved opposite surfaces and fitting between a pair of said projections, each pair of said projections being interlocking engaged with opposite grooved surfaces of a unit, and means at the sides of each strip for supporting said veneering units therein in alignment with other units on the wall.

8. The method of applying oppositely grooved veneering units to a wall by means of fastening strips having spaced projections, including preforming alternate projections to fit one groove of a unit, inserting a unit between each pair of projections with the preformed projection fitting in one groove of said unit, and then bending the other projection into interlocking engagement with the opposite groove of said unit.

9. In a method of applying veneering units having grooved opposite surfaces to a wall by means of fastening strips having spaced projections, the steps of preforming alternate projections to fit in one groove of each unit before the unit is applied, and bending the other projections into interlocking engagement with the opposite groove of each unit after said unit is applied.

NELSON O. GEISINGER. 50
